(57) **CLAIM**

We claim the ornamental design for a control panel for washing machine, as shown and described.

DESCRIPTION

FIG. 1 is a perspective view of a control panel for washing machine showing the new design:

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

Broken lines illustrate environmental condition only and form no part of the claimed design.
